UNITED STATES PATENT OFFICE.

JAMES C. HANES AND CLEMENS C. GOOLE, OF SAN FRANCISCO, CALIFORNIA.

PERFORATING, SEALING, AND MEASURING DEVICE.

Application filed April 10, 1926. Serial No. 101,180.

This invention relates to can opening devices and has for its primary object the provision of a novel form of device of this character which will be effective for the purpose intended, and which will be characterized by a punch or can perforating instrument for forming a pouring or discharge opening in the can or container, and a manipulating portion so designed as to simplify the operation of forming the opening and which, incidentally, acts in the dual capacity of a measure or charge holder and a seal, so that after an opening has been formed in the can or container, the device can be arranged in operative sealed engagement with respect to the opening; and which said device is freely removable from the opening so that any part of the can's contents can be poured into the measure or charge holding portion.

Another object of the invention is to provide a device of this character which may be operated with little manual effort in the act of forming an opening in the can.

A still further object of the invention is to provide a device of this character which may be operated without causing injury to the hands when forming the opening.

With the above and other objects in view, which will appear as the nature of the invention is better understood, the same consists in the improved construction and novel arrangements of parts which will herein-after be fully described and particularly pointed out in the claim.

In the accompanying drawings has been illustrated a single and preferred form of the invention, it being, however, understood that no limitations are necessarily made to the precise structural details therein exhibited, but that changes, alterations and modifications within the scope of the claim may be resorted to when desired.

Figure 1 is a vertical section through a portion of a can showing an application of the invention thereto to form an opening in the can, the measure portion of the invention being shown partly in full lines and partly in section; and

Figure 2 is a top plan view thereof.

The device is admirably useful in connection with metallic cans or containers such as those intended for the temporary storage of ground or pulverized coffee, cereals, condiments and other matter capable of being poured from the container

when an opening has been formed in one of its walls; or it may be used in conjunction with receptacles or containers intended to hold medicines, chemicals, disinfectants, insecticides, etc. We are not particularly interested in the kinds of materials to be employed, nor in the size or proportion of parts, as this may be left to ordinary discretion, according to the purpose to which the invention is to be put.

In carrying the invention into practice, we preferably employ a cupped manipulating portion 5 which is hollow and substantially frustro-conical, the upper large end 70 being open as indicated, and the lower small end closed by a flat bottom 6. The marginal edge of the portion 5 is rolled preferably at 7, and within the roll is inserted a reinforcing wire or strip 8 to give strength to 75 the structure and at the same time offer a marginal surface which will be easy to the palm of the hand when the latter is made to rest thereon.

The portion 5 may be of any appropriate size, but when the device is used in conjunction with coffee cans, the proportion of said portion 5 is calculated so as to constitute a defined measure. For instance, its capacity may be equal to the capacity of 85 an ordinary tea-cup.

Axially of the flat bottom 6, and fixedly secured thereto by welding, or in any other suitable well-known manner, is a depending cylindrical punch or penetrating instrument 9 having a straight cutting edge 10 and a connecting spiral cutting edge 11. This construction gives to the base of the instrument 9 a relatively sharp starting point 12. The diameter of the instrument 9 may be suitably calculated so that it will produce in a can an opening of desired size.

In using the invention, the cupped portion 5 is grasped in the hand of the operator, preferably at the palm thereof, so that portions of the hand may come in free bearing contact with the roll edge 7. The air contained within the cup when the hand is associated with the latter as just set forth, lends a cushioning effect against the hand when pressure is applied to the device in the act of penetrating a can. The point 12 of the penetrating instrument 9 is now placed in contact with the crown wall A of the can B, and force in a downward direction is applied to the device so that the

instrument 9 passes through the crown, and in the act of so doing it forms an opening 13 therein. In coffee cans, it is desirable to form the opening 13 near the marginal bead of the crown A so that in the act of pouring the coffee from the can, no great difficulty will be experienced in a discharge of the entire contents of the can.

When the opening is formed in the can, 10 the instrument 9 may normally constitute a stopper for the opening, and the base 6 of the cupped portion 5 comes in flat contact with the can to effectively seal the opening in the wall A. This is exceedingly desirable 15 in cases where the contents of the can might be impaired by undue exposure to atmospheric air. When pouring the contents from the can, the cup 5 may be used as a measure for determining the discharge of 20 material from the can for any purpose

whatsoever; for instance, a predetermined amount of ground coffee in proportion to so much water when it is desired to boil the coffee for beverage purposes.

We claim:—

A device of the class described comprising a perforating instrument adapted to form a pouring opening in a can, and a manipulating portion secured to said instrument at one end thereof and provided with a flat seat, the instrument serving as a closure for the opening when formed and the seat serving to close over the opening and to rest against portions of the can around the opening, said manipulating portion being of cup formation having an upper open end whose diameter is greater than that of the base of said portion.
